UNITED STATES PATENT OFFICE.

WILLIAM I. SPANGLER, OF TARLTON, OHIO.

TARGET TRAP.

Application filed August 7, 1922. Serial No. 579,991.

To all whom it may concern:

Be it known that I, WILLIAM I. SPANGLER, a citizen of the United States, residing at Tarlton, in the county of Pickaway and 5 State of Ohio, have invented certain new and useful Improvements in Target Traps, of which the following is a specification.

The primary object of the invention is to produce a mechanism in which the action 10 of a dead center will be eliminated and allow a simple and rigid construction whereby the carrier and carrier arm can be reset for action.

A further object of the invention is to 15 construct and arrange the carrier in such angular relation with respect to the supporting frame as to cause the target to lie close to the carrier to eliminate additional mechanism for holding the target as it slides 20 along the carrier. In this manner horizontal flight of the target is prevented, and the target caused to be projected at an angle, thereby presenting to the marksman more surface for his mark.

25 With these and other objects in view, as will appear as the description proceeds, the invention consists in the novel features of construction, combinations of elements and arrangements of parts, and hereinafter to 30 be fully described and pointed out in the appended claims.

In the accompanying drawing:

Figure 1 is a top plan view,

Figure 2 is a side view,

35 Figure 3 is a sectional view on the line 3—3 of Figure 1,

Figure 4 is an enlarged fragmentary side elevation of the mounting,

40 Figure 5 is a sectional view on line 5—5 of Figure 4, and

Figure 6 is a detail sectional view through the mounting.

Referring to the drawing 1 designates a base upon which is rotatably mounted in the 45 customary manner an inclined frame 2 which includes a pair of spaced upper and lower bars 3 and 4, respectively, the bar 3 having a latch 5 carried thereby which may be of any approved construction and serves 50 to hold the carrier 6 in its set position.

The carrier comprises an elongated bottom plate 7, one edge of which terminates in a vertical flange 8 and upon which is secured a plate 9 in which is fixed a rubber 55 strip 10. The rear end of the plate 7 is provided with a semi-circular flange 11

which is a continuation of the flange 8, there being a post 12 adjustably carried by the plate 7 and against which the target 13 rests, and at a time when the carrier is in 60 its operative or set position. The post has engaged thereon a rubber sleeve 14 which serves as a cushion to prevent injury to the target.

The post 12 may be selectively engaged in 65 any of the perforations 14' formed in the carrier, and since the target 13 rests against this post it will be obvious that upon adjusting this post backwardly or forwardly that the target will leave the carrier earlier or 70 later for the purpose of regulating the angularity of the target in relation to the carrier. For instance, if the stop is set near the extreme inner end of the carrier, the angularity of the target will be greater and 75 vice versa. In other words, when the arm is swung and if the stop is comparatively far out upon the arm the target will leave the carrier arm at certain points longitudinal with the axis of the arm.

80 In order to swingably mount the carrier 6 on the frame 2, a shaft 15 is employed and has its upper end fixed in a sleeve 16 rotatably mounted in the upper bar 3 of the frame, the lower end of said shaft being 85 journaled in a bearing 17 formed in the bar 4 of said frame. The upper end of the sleeve 16 has a carrier arm 18 formed integral therewith, said arm being in the same 90 parallel plane as the bar 3.

95 The plate 7 of the arm 6 has a pair of lugs 19 formed upon its lower surface, the outermost one being of greater height than the inner one so that when the carrier is placed on and secured to the carrier arm 18 the inclination of the carrier will be sharper than the inclined plane of the bar 3, or in other words the carrier arm will be disposed in obtuse angular relation with respect to the shaft 15 whereby the targets 13 will be projected at a greater inclination or angle when projected from the carrier. The lower end of this sleeve is provided with an extension 20 which carries a depending pin 21, the purpose of which will appear later.

100 Pivotally mounted on the shaft 15 immediately below the sleeve 16 is a link 22 carrying a depending bolt 23 and to which is pivotally connected the forward end of a rod 24, the rear end of which is pivotally 110 connected to a lever 25, said lever being pivotally mounted on the base 1. This bar

is swung on its pivot by a link 26 which may be operated in the customary manner.

A plate 27 is provided and is pivotally connected to the shaft 15, the inner end of which has pivotally connected thereto the forward end of a rod 28, the rear end of which is secured to the forward end of the coil spring 29, the rear end of the spring being connected to the bar 30 of the frame 10 2 by a rod 31.

A collar 32 is mounted on the shaft 15 and retained thereon by a set screw 33 which also serves to secure the lower end 15 of the coil spring 34, the upper terminal 15 of which being engaged with a stud 35 on the plate 27. Since the bolt 23 is engaged with the plate 27 forwardly of the shaft 15 it will be apparent that when the rod 24 is pulled rearwardly that the plate 27 will 20 swing on its pivot and simultaneously pull the bolt 28 forwardly, thus placing the spring 29 under tension. As the rod 24 is moved rearwardly upon manipulating the link 26 the carrier arm 18 will be swung 25 rearwardly until it engages the latch 5 which retains said arm in its set position to receive the targets 13. The latch 5 is operated to release the carrier arm when the rod 24 is moved forwardly, the spring 29 serving 30 to rapidly swing the carrier 6 forwardly to eject the target from the carrier, the forward corner of the plate 7 being bent downwardly, as at 35 to permit the target to slide freely therefrom. Owing to the fact 35 that the pin 21 is in the path of movement of the rear portion of the plate 27 the bushing 16 will be rotated thus swinging the carrier arm.

The carrier 6 will swing forwardly until 40 the forward end of the plate 27 strikes the bar 36 of the frame 2, as shown in Figure 5, whereupon the shaft 15 will make a fraction of a revolution, the forward swinging movement thereof being yieldably limited 45 by the spring 34, since this spring has one terminal connected to the plate 27 and the other with the collar 32 fixed to said shaft. It will be of course apparent that when the

plate 27 strikes the bar 36 that the movement of the carrier and carrier arm will not 50 be immediately limited, but will continue to swing forwardly against the action of the spring 34 until said spring has overcome the momentum of said arm and carrier, whereupon the carrier 6 will be returned to its unset or normal position, and at which time will be in a position to prevent a dead center, thus permitting the carrier to swing easily to its set position. 55

What is claimed is:

1. In a target trap, a base, a frame rotatably mounted thereon, a shaft pivotally connected with the frame, a carrier connected with the shaft, a plate pivotally mounted on the shaft, a spring yieldably connecting the shaft and plate, said plate being adapted to have one end engage the frame during the forward swinging movement of the carrier to permit the spring to yieldably limit the movement thereof when 70 said plate engages the frame, and means for rotating the shaft to swing the carrier forwardly.

2. In a target trap, a frame, a shaft mounted thereon, a target carrier fixed to 75 the shaft, a plate pivotally mounted on the shaft, a spring connecting the shaft and plate, said plate being adapted to have one end engage the frame as a carrier swings forwardly, said spring serving to yieldably 80 limit the movement of the carrier during the forward swinging movement thereof.

3. In a target trap, a frame, a main shaft, a main projecting spring, a plate associated with a shaft and connected with a 85 main spring, stopping means, a target carrier, means for connecting the carrier with the plate, a flexible means for allowing the carrier to continue past dead center after the plate has engaged the stopping means 90 and said means to return the carrier to normal or unset position.

In testimony whereof I affix my signature.

WILLIAM I. SPANGLER.
